REFRIGERATING APPARATUS

Otto M. Summers, Dayton, Ohio, assignor to General Motors Corporation, Dayton, Ohio, a corporation of Delaware

Application December 31, 1935, Serial No. 56,988

5 Claims. (Cl. 62—89)

This invention relates to refrigeration and particularly to a refrigerator cabinet having novel food storage compartment arrangements therein.

5 In the production of mechanically refrigerated household refrigerator cabinets it is an ever increasing problem to provide a cabinet in which food products of various shapes and sizes relative to one another may be stored at their different proper temperatures respectively without materially increasing the size of a cabinet and without unduly destroying a part of a predetermined storage area provided in the cabinet. With this problem in view the objects of applicant's invention and the novelty of the structure disclosed will become apparent.

An object of the present invention is to provide an improved refrigerating apparatus of the type including a plurality of food storage compartments in a chamber of a refrigerator cabinet and which compartments are cooled to different temperatures relative to one another.

Another object of the invention is to mount or install cooling elements or evaporators of a closed refrigerant circulating system within a chamber of a refrigerator cabinet so as to divide the interior of the chamber into a plurality of food storage compartments and so as to provide a refrigerated shelf or support for certain foods to be stored in the refrigerator cabinet.

30 A further object of the invention is to provide an improved shelf arrangement which divides a refrigerated chamber into a plurality of compartments and cooperates with the chamber so as to permit the storage within the chamber of variously shaped articles without materially reducing or impairing the total food storage capacity thereof.

In carrying out the foregoing objects it is a 40 more specific object of the present invention to provide an improved shelf for a food storage chamber of a refrigerator cabinet which shelf is designed to permit tall bottled beverages, supported by a support below the shelf, to be located along a side thereof while at the same time being arranged to permit articles to occupy the space along the side of the shelf and supported thereupon when tall bottled beverages are not disposed in the space provided therefor.

45 Further objects and advantages of the present invention will be apparent from the following description, reference being had to the accompanying drawings, wherein a preferred form of the present invention is clearly shown,

50 In the drawings:

Fig. 1 is a vertical sectional view looking from the front to the rear of a refrigerator cabinet having my invention embodied therein; and

Fig. 2 is a vertical sectional view through the cabinet shown in Fig. 1 and taken on the line 5—5 thereof.

Referring to the drawings, I have shown in Fig. 1 thereof, for the purpose of illustrating my invention, a refrigerator cabinet of the household type generally represented by the reference character 10. The cabinet 10 includes a plurality of insulating walls 11 surrounding a food storage chamber provided within the cabinet. The food storage chamber, surrounded by the insulating walls 11, is divided into two chambers 15 12 and 13 by suitable metallic lining members 14 and 15 respectively. The upper lining member 14 is of box-like form and has one open side disposed adjacent an access opening 16 provided in the front of cabinet 10 and adapted to be 20 closed by the door 17 (See Fig. 2). The lower lining member 15 has an open side, similar to the open side of lining 14, and also has an open top provided with outwardly flared edge portions 18 which fit over and are welded or otherwise 25 securely fastened to the bottom portion of lining 14 so as to position the upright walls of both lining members in vertical alignment. This method of forming the inner walls of the area 30 surrounded by the insulation 11 and door 17 and of dividing that area into two chambers reduces manufacturing costs in that it eliminates the handling of large lining members and facilitates assembly of the cabinet. The two liners 14 and 15, after having been secured together in the 35 manner described, are fastened, in any suitable and well-known manner, to and supported by a wooden frame which surrounds the door opening 16 of the cabinet.

Each of the chambers 12 and 13 of cabinet 10 40 are divided into a plurality of compartments for the purpose set forth in the objects of the present invention. For example, chamber 12 has a sheet metal member 21 horizontally positioned therein and secured to the upright chamber 45 walls by resilient bumpers or the like 22 which fit into depressions 23 provided in the lining member 14. The member 21 forms a food support or shelf in chamber 12 and divides this chamber into an upper food storage compartment 24 and a lower food storage compartment 25. An evaporator 27, comprising superimposed sheet metal portions having refrigerant passages provided therebetween, is bolted or otherwise secured to the underside of shelf member 21 and 55

extends substantially entirely across the compartment 25. The space between evaporator 27 and member 21 forms a sharp freezing compartment 28 for the reception of receptacles such as ice trays 29, adapted to contain a substance to be congealed or frozen by the cooling action produced by evaporator or cooling element 27. The compartment 25 below evaporator 21 may be utilized for the storage of certain foods such as 10 frozen fish, meats, etc., to be maintained at a very low temperature while compartment 24 may be utilized for the storage of certain other foods not required to be maintained at such a low temperature. A door 31 (see Fig. 2) is pivotally secured to the front edge of shelf member 21 as at 32 and is employed to prevent free air circulation to and from compartment 25 so as to provide a temperature difference between this compartment and various other compartments 15 in the cabinet, and so as to render compartment 25 suitable for the storage of frozen foods which are to be maintained at a temperature preferably below 32° F. It is to be understood that the cooling element or evaporator 27 is always maintained below 32° F. in order to produce ice and to properly cool frozen foods stored in compartment 25.

In addition to the foregoing it is obvious that present-day requirements render it necessary to 30 provide for the proper refrigeration in household refrigerator cabinets of bottled beverages such as ginger ale, beer and milk or other food products containing a certain amount of butter fat. To this end my improved structure is provided with a partition 34 which is in the form of a cooling element or evaporator and comprises superimposed sheet metal portions having a refrigerant passage or passages therebetween. The partition or cooling element 34 is horizontally disposed within the chamber 13 and extends substantially from one vertical wall to other vertical walls thereof to divide the chamber into an upper compartment 35 and a lower compartment 36. Cooling element or evaporator 40 34 forms a support for food products placed within compartment 35 and is secured in place by suitable resilient bumpers or the like 38 fitted into depressions 39 provided in the lining member 15 of chamber 13. The compartment 36 is considerably higher than other compartments 45 formed in cabinet 10 and is therefore adapted to receive, in vertical position, a plurality of bottled beverages such as ginger ale, beer and milk. The entire area of compartment 36 is not required for such bottled beverage storage and the 50 distance from the front to the rear of chamber 13 along the side walls thereof, which affords room for two rows of such bottled beverage, is normally sufficient. Quite frequently the path 55 along one side wall within compartment 36 is ample storage space for bottled beverages. It is to be understood that whatever storage space is provided in a cabinet for bottle beverages it is desirable to have such space arranged so that 60 during the act of placing bottled beverages in the refrigerated compartment or removing same therefrom tilting or tipping of bottles will be unnecessary. My improved construction has therefore been arranged to meet these desirables 65 and to afford a storage or food supporting surface intermediate the space to be occupied by bottled beverages along the side walls of chamber 13. I provide a sheet metal shelf 41 within compartment 36 which shelf is supported from 70 the evaporator 34 by being suspended therefrom

by a pair of suitable brackets 42 located at the front of chamber 13 and a pair of conventional shelf pegs or hooks 43 secured to the rear wall of liner 15. The shelf 41 is perforated as at 44 (see Fig. 2) for affording free circulation of air 5 within compartment 36. It will be noted that shelf 41 is spaced from the side walls of compartment 36 and that no part thereof or of the supports therefor obstruct the path for the reception and storage of bottled beverages, thus 10 bottles can be moved into and out of compartment 36 through the door opening 16 without tipping or tilting same. Due to the taper at the top of most bottled beverages my shelf 41 is made of a size so that its side edges extend into 15 close proximity to the upper tapered portion of the bottles supported adjacent the chamber walls. By extending shelf 41 beyond the greater diametered or lower portion of the bottled beverages the space between the edge of shelf 41 and 20 the vertical side wall of compartment 36 is greatly reduced as compared to other prior shelf arrangements wherein a side portion of a shelf is moved into the area occupied by the shelf proper or is entirely removed from the shelf and 25 the refrigerator cabinet to provide space for the storage of tall bottled beverages. This improved method of providing a food supporting shelf within the compartment 36 thereby permits 30 dishes or plates to be supported on the shelf 41 without danger of being tilted or tipped therefrom. For example, a plate or dish supported on shelf 41 can be moved outwardly of the side edge of the shelf, into the space adapted to be occupied by tall bottles, without becoming unbalanced and sliding off the shelf. Thus my improved shelf arrangement permits the storage 35 of food products along the bottom of the relatively tall space provided for bottles in compartment 36 and also permits the upper part 40 of this space to be occupied by food products placed in dishes and supported upon shelf 41 when no bottles are located in the space therefor within compartment 36.

The evaporators or cooling elements 27 and 34, 45 which form a part of a closed refrigerant circulating system mounted in or associated with cabinet 10, are connected in series relation with the refrigerant circulating unit of the refrigerating system. The refrigerant circulating unit 50 of the refrigerating system includes a compressor 51 operatively connected, through belt and pulley connections 52, with an electric motor 53. Motor 53 is controlled by a switch 54 interposed in the power line leading thereto. Switch 54 is 55 preferably of the snap acting type and includes a bellows 55 having pipe connection 56 with a thermostat bulb 57. Bellows 55 is moved to actuate switch 54 into open or closed position in a manner well known to those skilled in the art to stop or start motor 53. Operation of motor 53 and consequently compressor 51 causes the compressor to withdraw evaporated or gaseous refrigerant from evaporator 27 through pipe or conduit 58. The compressor 51 compresses the 60 gaseous refrigerant and forwards same under pressure, through the pipe 59, to a condenser 61. The compressed refrigerant is cooled and liquefied in condenser 61 in any suitable and well-known manner and the liquid refrigerant flows 65 into a receiver 62 where it is stored prior to being circulated, through conduit 63, to evaporator 34 under the control of a suitable expansion valve or device 64. After passing through refrigerant passages provided in the sheet metal 70 75

evaporator 34 and partially expanding or vaporizing therein, to cool chamber 13, the refrigerant is directed, by pipe 65, to the upper evaporator 27 and admitted thereto under the control of a second expansion device or valve 66. The refrigerant is completely evaporated or vaporized in evaporator 27 and returned in the manner described to the compressor 51 of the refrigerant circulating unit to be recondensed and liquefied. 10 The thermostat 57 alone controls the operation of the refrigerant liquid and circulating unit in response to the temperature of evaporator 34 in order to give preference to the cooling or refrigerating of chamber 13 so as to insure proper 15 preservation of food products, such as milk and other foods containing butter fat while the temperature of evaporator 27 may vary from 32° F. to far below this temperature without impairing proper preservation of the frozen foods in compartment 25 and substance in the trays 29 of the freezing compartment 28. Ordinarily evaporator 34 is maintained between, for example, 40° and 50° F. thus rendering the same ideal for supporting thereon lettuce and other 25 green vegetables without freezing same. These temperature limits of evaporator 34 are sufficient to prevent bacterial formations in milk and other butter fat containing foods and are sufficient to maintain bottled beverages such as beer 30 and ginger ale at the proper temperature.

From the foregoing it will be apparent that I have provided an improved refrigerating apparatus wherein a plurality of compartments in a refrigerator cabinet are maintained at different 35 temperatures relative to one another thus providing a household refrigerator cabinet with compartments for various food products that require certain temperatures. The improved structure also substantially isolates certain foods from certain other foods to prevent the transmission of odors from one to the other. My improved shelving structure for the lower compartment of the apparatus disclosed permits various arrangements of foods in the compartment without 40 losing any of the total food storage area in the compartment. In other words, when bottled beverages are not stored alongside of the shelf in the lower compartment of the cabinet my improved shelf is, by virtue of its extension into 45 close proximity of the walls of the cabinet, substantially the equivalent of a shelf which extends continuously throughout the entire horizontal cross-sectional area of the refrigerated chamber.

While the form of embodiment of the invention 55 as herein disclosed, constitutes a preferred form, it is to be understood that other forms might be adopted, all coming within the scope of the claims which follow.

What is claimed is as follows:

1. A refrigerating apparatus comprising in combination, a cabinet including a plurality of vertical and horizontal walls forming a chamber therein, a metallic member superimposed upon another metallic member and being secured thereto to divide said chamber into a plurality of chambers, means dividing the uppermost of said plurality of chambers into superimposed horizontally extending food storage compartments, means dividing the lowermost of said plurality of chambers into superimposed horizontally extending food storage compartments, one of said means comprising a flat sheet metal member extending continuously and substantially entirely across the chamber which it divides, an evaporator of a refrigerating system carried by said

flat sheet metal member and spaced therefrom to form a sharp freezing compartment therebetween, the other of said means comprising a substantially flat plate-like sheet metal evaporator extending continuously and substantially entirely across the chamber which it divides, means for supplying liquid refrigerant to said second named evaporator, and means for conveying refrigerant from said second named evaporator to said first named evaporator. 10

2. A refrigerating apparatus comprising in combination, a cabinet including a plurality of vertical and horizontal insulating walls defining a chamber therein, a plurality of metallic lining members disposed one upon the other to divide said chamber into a plurality of chambers, and forming the walls of said plurality of chambers, means dividing the uppermost of said plurality of chambers into superimposed horizontally extending food storage compartments, means dividing the lowermost of said plurality of chambers into superimposed horizontally extending food storage compartments, said first named means comprising a flat sheet metal member extending continuously and substantially entirely across said uppermost chamber, an evaporator of a refrigerating system comprising superimposed secured together sheet metal portions carried by said flat sheet metal dividing means, said evaporator being spaced from the bottom of said flat sheet metal member to provide a sharp freezing compartment between the evaporator and the flat sheet metal dividing means, said second named means comprising a substantially flat plate-like sheet metal evaporator extending continuously and substantially entirely across said lowermost of said plurality of chambers, a door for closing said chambers and said food storage compartments, means for supplying liquid refrigerant to said second named evaporator, and means for conveying refrigerant from said second named evaporator to said first named evaporator. 25

3. A refrigerating apparatus comprising in combination, a cabinet including a plurality of vertical and horizontal insulating walls defining a chamber therein, a plurality of metallic lining members disposed one upon the other to divide said chamber into a plurality of chambers, and forming the walls of said plurality of chambers, means dividing the uppermost of said plurality of chambers into superimposed horizontally extending food storage compartments, means dividing the lowermost of said plurality of chambers into superimposed horizontally extending food storage compartments, said first named means comprising a flat sheet metal member extending continuously and substantially entirely across said uppermost chamber, an evaporator of a refrigerating system comprising superimposed secured together sheet metal portions carried by said flat sheet metal dividing means, said evaporator being spaced from the bottom of said flat sheet metal member to provide a sharp freezing compartment between the evaporator and the flat sheet metal dividing means, the compartment formed below said flat sheet metal dividing means and the horizontal portion of one of said metallic lining members having a closure member for preventing free air circulation to and from said compartment, an insulated door for closing said chambers and the other compartments formed in said cabinet, said second named means comprising a substantially flat plate-like sheet metal evaporator extending continuously and substan- 75

5
tially entirely across said lowermost of said plurality of chambers, means for supplying liquid refrigerant to said second named evaporator, and means for conveying refrigerant from said second named evaporator to said first named evaporator.

10
4. A refrigerating apparatus comprising in combination, a cabinet including a plurality of vertical and horizontal insulating walls defining a chamber therein, a plurality of metallic lining members disposed one upon the other to divide said chamber into a plurality of chambers, and forming the walls of said plurality of chambers, means dividing the uppermost of said plurality of 15 chambers into superimposed horizontally extending food storage compartments, means dividing the lowermost of said plurality of chambers into superimposed horizontally extending food storage compartments, said first named 20 means comprising a flat sheet metal member extending continuously and substantially entirely across said uppermost chamber, an evaporator of a refrigerating system comprising superimposed secured together sheet metal portions carried by said flat sheet metal dividing means, said evaporator being spaced from the bottom of said flat sheet metal member to provide a sharp freezing compartment between the evaporator and the flat sheet metal dividing means, the compartment 25 formed below said flat sheet metal dividing means and the horizontal portion of one of said metallic lining members having a closure member for preventing free air circulation to and from said compartment, an insulated door for closing said 30 chamber and the other compartments formed in said cabinet, said second named means comprising a substantially flat plate-like sheet metal evaporator extending continuously and substantially entirely across said lowermost of said

5
plurality of chambers, a shelf within the compartment below said second named evaporator, said shelf having at least one of its side edges terminating in spaced relation to the chamber side wall to form a high narrow path along the 10 side of the shelf for the reception of bottled beverages to be stored within said cabinet, means for supplying liquid refrigerant to said second named evaporator, and means for conveying refrigerant from said second named evaporator to 15 said first named evaporator.

15
5. A refrigerating apparatus comprising in combination, a cabinet having a compartment therein, an access opening for said compartment in one wall of said cabinet and normally closed by a door, means for cooling the interior of said compartment, means disposed horizontally within said compartment and dividing same into an upper food storage space and a lower food storage space, a shelf spaced from said compartment 20 dividing means and disposed horizontally within said lower food storage space to divide same into a plurality of superimposed smaller storage spaces, said shelf extending throughout the major portion of the width of the compartment and 25 from the rear wall of said compartment to a point closely adjacent said door to form a top wall portion of the lower of said smaller storage spaces and a flat food supporting surface for the upper of said smaller storage spaces, 30 and said shelf having its side edges spaced from the side walls of said compartment to provide relatively high, narrow unobstructed paths on each side of said shelf extending entirely from the front to the rear of said compartment intermediate said compartment dividing means and the bottom wall of the lower of said smaller storage spaces for the reception of tall articles.
